(57) CLAIM

The ornamental design for a mandoline slicer, as shown and described.

DESCRIPTION

FIG. 1 is an upper perspective view of a mandoline slicer;

FIG. 2 is a lower perspective view thereof;

FIG. 3 is a left side view thereof;

FIG. 4 is a right side view thereof;

FIG. 5 is a rear view thereof;

FIG. 6 is a front view thereof;

FIG. 7 is a top plan view thereof; and,

FIG. 8 is a bottom plan view thereof.

The broken lines in the drawings depict portions of the mandoline slicer that form no part of the claimed design.
